Oscar Geir
ATTORNEY

UNITED STATES PATENT OFFICE.

ABRAHAM ROSEN, OF NEW YORK, N. Y., ASSIGNOR TO SILBERSTEIN-ROSEN AND SONS
OF NEW YORK, N. Y.

SEWING-MACHINE ATTACHMENT.

1,172,393.

Specification of Letters Patent. Patented Feb. 22, 1916.

Application filed May 24, 1915. Serial No. 29,966.

To all whom it may concern:

Be it known that I, ABRAHAM ROSEN, a citizen of the United States, and a resident of New York, in the county of New York 5 and State of New York, have invented certain new and useful Improvements in Sewing-Machine Attachments, of which the following is a specification.

This invention relates to improvements in devices for guiding fabrics with respect to the sewing line whereby a uniform margin or hem may be attained on goods of unlimited length.

The principal object is to provide a novel 15 and thoroughly efficient device, which may be attached to any of the ordinary types of sewing machines, that will fold and deliver, in advance of the needle, any length of fabric, and particularly such as is used in 20 the manufacture of handkerchiefs, the marginal folding or depth of hem being adjustable and the material operatively guided and controlled automatically without manual labor or constant supervision, thereby 25 making it possible for an operator to attend to several machines simultaneously.

A second object is to provide such attachments of extreme simplicity of construction, readily attachable and operable with entire 30 facility by ordinary skilled attendants.

These objects are attained by the novel construction and disposition of parts hereinafter described and shown in the annexed drawing, forming part of this specification, 35 and in which:—

Figure 1 is a partial side elevation of a sewing machine, showing the application of the attachment. Fig. 2 is a plan view of the attachment. Fig. 3 is a transverse sectional view, taken on line 3—3 of Fig. 2, and Fig. 40 4 is an enlarged longitudinal sectional view, showing the goods guide.

The device is attached to the table 10 of the sewing machine at the front, near the 45 end, in such position as to cause the fabric to move in the path of the needle 11 under the presser-foot 12 operated in the head 13. It comprises a bar 14 having angularly

turned ends 15 extending away from the table 10 and pivotally secured to these ends 50 by bolts 17 are arms 16, the outer ends of the arms having extending between them a round rod 18 having adjustably mounted on it a pair of slidable guides 19 between which the fabric moves. Also adjustably engaged 55 to the angular ends 15 are a pair of slotted links 20, held by the bolts 21 and formed integral with a bar 22, the bar being adjustable angularly and slotted to receive an adjustable guide 23 which may be clamped in 60 any desired position by the set screw 24. An offset portion 25 of the guide 23 extends alongside the bar 22, and is turned so as to form a loop 26 having a reentrant member 27 extending backward about the portion 25, being spaced therefrom to receive the fabric and fold it upwardly at an angle of substantially 90 degrees preliminary to its passage through the hemmer 29. This 65 operation is further assisted by the plate 29 70 which forms part of the hemming attachment customarily employed.

From the foregoing it will be obvious that a strip of material of any length whatever will be properly supported by the rod 18, 75 between the guides 19, and the edge turned or folded over as it passes through the loop 26 which is capable of adjustment lengthwise with respect to the hemmer plate 29.

When once a piece of fabric has been inserted no further attention need be paid to it thereby enabling an operator to care for several machines dividing their time between them as may be required.

Having thus described my invention and specified its application and use, what I claim as new and desire to secure by Letters Patent, is:—

1. In a strip guiding attachment, a frame, a horizontal rail, bars pivoted to said frame 90 carrying said rail whereby it may be raised or lowered, guides adjustable lengthwise on said rail, a bar having downturned slotted ends pivoted exteriorly of said frame, means for securing said bar in an adjusted 95 position, a looped fabric folder having an

open outer end, adjustable lengthwise of said bar and, means for maintaining said folder in an adjusted position on said bar.

2. In a strip guiding attachment, a frame, 5 an adjustable support rail over which the fabric passes, guides movable on said rail, a folder into which the fabric may be freely entered from one end thereof, supports for said folder, said supports being adjustable

angularly, vertically and laterally with respect to said frame, and means for securing said folder in an adjusted position.

Signed at New York, in the county of New York and State of New York this twenty-first day of May A. D. 1915.

ABRAHAM ROSEN.

Witness:

DAVID E. KOHAN.
